CLAIM

The ornamental design for a protective garment, as shown and described.

DESCRIPTION

FIG. 1 is a front view of the protective garment showing our new design;

FIG. 2 is a left side view thereof, a right side being identical to the left side;

FIG. 3 is a back view thereof;

FIG. 4 is a front view thereof, with sleeves of the protective garment outstretched;

FIG. 5 is a rear view thereof, with the sleeves outstretched; and,

FIG. 6 is a front-left perspective view thereof.

The broken lines showing portions of the protective garment form no part of the claimed design.
